UNITED STATES PATENT OFFICE.

SOLON OWEN CAMPBELL, OF EAST PERU, IOWA, ASSIGNOR OF ONE-HALF.
TO E. C. TILLEY, OF KANSAS CITY, MISSOURI.

FENCE-POST.

SPECIFICATION forming part of Letters Patent No. 784,033, dated March 7, 1905.

Application filed June 25, 1904. Serial No. 214,171.

To all whom it may concern:

Be it known that I, SOLON OWEN CAMPBELL, a citizen of the United States, residing at East Peru, in the county of Madison and State of 5 Iowa, have invented certain new and useful Improvements in Fence-Posts, of which the following is a specification.

This invention relates to that class of post structures embodying the use of a plastic body 15 and a metallic stay embedded therein.

The essential feature of the invention resides in the peculiar form of the stay, whereby the same may be very advantageously embedded in the body of the post in the operation 15 of molding the same. The stay provided for the post is also designed to perform the function of a lightning-arrester for the preservation of live stock, particularly when the post is utilized in fence structure.

For a full description of the invention and the merits thereof and also to acquire a knowledge of the details of construction of the means for effecting the result reference is to be had to the following description and accompanying 25 drawings.

While the essential and characteristic features of the invention are susceptible of modification, still the preferred embodiment of the invention is illustrated in the accompanying 30 drawings, in which—

Figure 1 is a perspective view of a fence-post embodying my invention. Fig. 2 is a vertical sectional view. Fig. 3 is a perspective view of the stay, showing the parts there- 35 of assembled in proper position. Fig. 4 is a side elevation showing the application of the invention as a hitching-post. Fig. 5 is a horizontal sectional view bringing out the cruciform or winged formation of the post. Fig. 40 6 is a perspective view of the main stay-rod.

Corresponding and like parts are referred to in the following description and indicated in all the views of the drawings by the same reference characters.

The body 1 of the post is plastic, as before premised, being made of earthenware, burnt clay, cement, concrete, or any other substance suitable for the purposes of the invention, and this post in general form preferably tapers, as

shown most clearly in Fig. 1. The post in 50 transverse sectional view is preferably cruciform, having the wings 2, however. The latter may be of any number found desirable or best in the practical manufacture of the invention.

55

The stay, which comprises the essential feature of the invention, is composed of a plurality of stay bars or rods, one of the stay-bars being embedded in each wing 2, so as to effect a greater rigidity of the post structure and to 60 hold the elements of the plastic material from which the body 1 is made in compact solid condition. For the purposes of the description the stay consists of the main stay-bar 3 and a plurality of auxiliary stay-bars 4. The stay-bars are preferably made of metal and comprise longitudinal rods which mutually reinforce one another when embedded within the body 1. The main stay-bar 3 is of course embedded in one of the wings 2 of the post, the 65 ends of said bar 3, however, projecting beyond the opposite extremity of the body 1. The upper end of the stay-bar 3 is provided with a hook to be attached to the uppermost line-wire of a fence, the lower end extending so as to be 70 grounded. The connection of the upper end of the stay-bar 3 with the fence admits of arresting the lightning, which is grounded by the lower end of said stay-bar in a manner which 75 will be clearly comprehended. The manner of securing the auxiliary stay-bars to the main stay-bar 3 is peculiar, and for this purpose each of the bars 4 is provided at opposite extremities with a securing member in the form of a hook 5, which hook projects angularly 80 therefrom. The ends of the main stay-bar 3 are deflected, as shown at 6, to form a sort of shoulder, and the hooks 5 of the stay-bars 4 are adapted to engage the ends of the main 85 bar 3 adjacent the deflected portion of the shoulder 6 aforesaid. The stay-bars 4 are of different lengths, so as to admit of ready engagement of the hooks thereof with the stay-bar 3 without interference one with the other, and in view of the differential lengths of the 90 bars 4 the hooks thereof are engaged with the end portions of the bar 3 at different points, said hooks, however, lying adjacent one an-

other and in contact, if desirable. The hooks 5 are disposed in a plane about at a right angle to the bars 4 and are so formed as to admit of quick engagement of the bars 4 with 5 the main bar 3 when arranging the stay in the mold preparatory to the molding operation. When the stay-bars are arranged in proper relation in the mold, the plastic material is tamped about the same, and when the body 1 10 is hardened the stay will form a permanent part of the post in a manner clearly apparent.

Hooks 7 may be embedded in the length of the body 1 of the post, so as to provide means for attaching the line-wires of the fence there- 15 to, and said hooks 7 are suitably anchored in position.

Fig. 4 of the drawings illustrates a hitching-post, in which structure the upper end of the main stay-bar is looped, as shown at 8, and 20 the extremity thereof is embedded in the body 1. A ring 9 is inserted into the loop 8, so as to permit attachment of a hitching-strap to the post. The hitching-post is shown tapered toward its opposite ends. However, this is 25 immaterial in the contemplation of the invention.

Having thus described the invention, what is claimed as new is—

1. In a fence-post, the combination of a plastic body, a stay embedded therein, said stay being composed of a main stay-bar, a plurality of auxiliary stay-bars, and engaging members 30 projected from the ends of the auxiliary stay-

bars and engaging the end portions of the main stay-bar.

2. In a fence-post, the combination of a plastic body, a stay embedded therein, said stay being composed of a main stay-bar, a plurality of auxiliary stay-bars, and engaging hooks 40 projected from the ends of the auxiliary stay-bars and engaging the end portions of the main stay-bar.

3. In a fence-post, the combination of a plastic body and a stay embedded therein, the said stay being composed of a main stay-bar having its ends projected beyond the ends of the plastic body, a plurality of auxiliary stay-bars, and hooks projected from the ends of the auxiliary stay-bars and receiving the ends of the main stay-bar.

4. In a fence-post, the combination of a plastic body, a stay arranged therein, said stay being composed of a main stay-bar having its ends projected from the end portions of the plastic body, a plurality of auxiliary stay-bars, and hooks projected angularly from the ends of the auxiliary stay-bars and receiving the ends of the main stay-bar adjacent the projected portions thereof.

In testimony whereof I affix my signature in 60 presence of two witnesses.

SOLON OWEN CAMPBELL. [L. s.]
